(57) **CLAIM**

The ornamental design for a speaker with battery pack as shown and described.

DESCRIPTION

1.1: Perspective

1.2: Front

1.3: Left

1.4: Top

1.5: Bottom

1.6: Reference view

The characteristic features of the design lie in the shape; the broken lines indicate portions of the article that form no part of the claimed design; the back view is omitted because it is a mirror image of the front view; the right side view is omitted because it is a mirror image of the left side view; reproduction 1.6 is a reference view showing a mounting part protrudes and form no part of the claimed design.
